[57] CLAIM

The ornamental design for a reel hub for magnetic tape cassette or the like, as shown and described.

DESCRIPTION

FIG. 1 is a front elevational view of a reel hub for magnetic tape cassette or the like, showing my new design; FIG. 2 is a sectional view thereof, taken along line 2—2 in FIG. 1;

FIG. 3 is a rear elevational view thereof;

FIG. 4 is a right side elevational view thereof, the left side being a mirror image;

FIG. 5 is a top plan view thereof; and

FIG. 6 is a bottom plan view thereof.

FIG. 3

FIG. 4

FIG. 6

FIG. 1

FIG. 2

FIG. 5

FIG. 2
